(57) **CLAIM**

The ornamental design for a wire connector, as shown and described.

DESCRIPTION

FIG. 1 is a perspective view of the wire connector showing my new design;

FIG. 2 is an another perspective view of the wire connector showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a male connector of the wire connector showing my new design;

FIG. 10 is an another perspective view of the male connector of the wire connector showing my new design;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of a female connector of the wire connector showing my new design;

FIG. 18 is an another perspective view of the female connector of the wire connector showing my new design;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof; and,

FIG. 24 is a bottom plan view.

The broken line portion of the figure drawings is included to show portions of the article that form no part of the claimed design.

1 Claim, 11 Drawing Sheets
